(57) **CLAIM**

I claim the ornamental design for a blood glucose meter, as shown and described.

DESCRIPTION

FIG. 1 is a front, right perspective view of an ornamental design for a blood glucose meter;

FIG. 2 is front, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent the shaded areas represent the bounds of the claim, while all other broken lines are directed to environment and are for illustrative purposes only; the broken lines form no part of the claimed design.
